UNITED STATES PATENT OFFICE.

SAMUEL ANGROVE, OF PROVIDENCE, RHODE ISLAND.

VALVE LIFTER.

Application filed February 27, 1924. Serial No. 695,599.

This invention relates to improvements in the construction of a valve spring compressor employed more especially to facilitate the removal of motor valves, and the object of this invention is to provide a simple and practical construction of such a lifter which is strong and durable and which is susceptible to quick operation in compressing a valve spring and holding it in compressed position.

A further object of this invention is to so construct the device that it may be readily adjustable to operate on machines of different designs and sizes.

A still further object of this invention is to so construct a valve engaging shoe that the lifting pressure will be applied at a substantially uniform point notwithstanding the spring of the stock forming the frame-work of the device.

With these and other objects in view, the invention consists of certain novel features of construction, as will be more fully described, and particularly pointed out in the appended claims.

In the accompanying drawings:

Figure 1 is a side elevation of my improved valve spring compressor.

Figure 2 is a top view of the device with the threaded spindle and its operating handle removed, its position being indicated in dotted position.

Figure 3 is a plan view of the shoe for engaging the valve spring, removed from the device.

Figure 4 is a perspective view of the flanged nut used for adjustably supporting the arm in the frame.

Figure 5 is a perspective view of the adjustment for the valve spring compressor used to rest in the valve seat to provide a support for the spindle when the valve is removed.

With reference to the drawings, 10 designates the frame portion of this device which is provided with a plurality of angular openings 11 extending through the frame. At the upper ends of these openings and at substantially right angles thereto, I provide 50 T-shaped slots 12 having over-hanging lips

13 for the engagement of the flange 14 of a nut 15 which is internally threaded for engagement with an arm 16 shaped angularly in cross section to prevent rotation of the arm in the frame and adapted to extend 55 through any one of the openings 11 for different adjustments. The upper end of this square arm is threaded on its corners as at 17 to be supported and adjustably held in position in one of the openings 11 by means 60 of the nut 15 correspondingly internally threaded which is suitably knurled as at 18 to provide a means for readily longitudinally adjusting the arm with relation to the frame.

The lower end of the arm 16 is offset as at 19 to provide a foot portion which is suitably slotted in which the ear 20 of a shoe 21 is adapted to be secured by means of a screw 22. This shoe is bifurcated at one 70 of its ends providing arm portions 23 to extend on either side of the valve stem 24 for engagement with the lower end of the valve spring 25.

The bifurcated arm portions of the shoe 75 are suitably recessed as at 26 for the reception of the lower end of the valve spring in order that the shoe will not tend to be displaced from the spring when once in position, and I have provided upstanding detents 27 on this recessed portion for engagement with the lower end of the valve spring or the cup supporting the same through which the lifting pressure on the valve spring will be applied even though the shoe 85 is not at right angles to the valve stem due to the springing of the stock.

In order that I may compensate for the different positions of the arm 16 in the openings 11 in the frame, I have provided shoes 90 having shanks of different lengths which may be readily interchanged and attached to the foot 19 by removing the screw 22.

The frame 10 is provided with a bearing 95 28 internally threaded to support a correspondingly threaded spindle 29 in engagement therewith. The lower end of this spindle is pointed as at 30 to fit into the central hole in the head of a valve 31 and the upper end of this spindle is provided with a suit- 100

able hand-adjusting wheel 32 for rotating this spindle and drawing the foot 21 upwardly or towards the spindle to compress the valve spring 25 in order that the pin 33 or other securing means may be removed therefrom, after which the spring may be released by an opposite movement of the handle 32 and the valve removed.

It is often found difficult to withdraw the valve spring from position after the valve has been removed and in order that this may be readily done, I have provided a support 34 as shown in Figure 5 which is bowl-shaped or suitably rounded for engagement with the valve seat and which is provided with a central hub 35 having an opening 36 therein to receive and support the spindle for lifting the shoe to compress the valve spring, after which the shoe portion 21 and the lower end of the valve spring may be swung outwardly by rocking the support 34 on the valve seat due to its curved contour and the spring removed from the engine by the operation of the handle 32 to release the compression of the spring.

In the event the spindle 29 might become stuck in position, I have provided a boss 37 on the upper end of the handle 32 for receiving the tap of a hammer to dislodge any encrustation and free the spindle in its bearing 28.

It will be further observed that when the arm 16 is placed in the outermost opening 11 of the frame it will be engaged by the extended bearing leg 38 to support the arm against undue springing of the parts due to the increased leverage when the arm is in this outermost position.

My improved valve compressing device is very simple in construction and yet is effective in its operation and is so designed that it may be quickly applied to an engine and manually adjusted by the operation of the knurled nut 18 when in close proximity to the valve and by the provision of a quick acting threaded spindle the valve spring may be compressed by but a minimum number of revolutions of the spindle thus requiring but the minimum time for withdrawing the supporting pins from the valve stem.

The foregoing description is directed solely towards the construction illustrated, but I desire it to be understood that I reserve the privilege of resorting to all the mechanical changes to which the device is susceptible, the invention being defined and limited only by the terms of the appended claims.

60 I claim:

1. A valve spring compressor comprising a frame disposed at substantially right angles to the valve stem when used and having a plurality of spaced apart openings there-
65 in, an arm carried by said frame and adapt-

ed to be positioned in any one of said openings, means for adjustably holding said arm in its opening, a shoe on the lower end of said arm for engaging the spring to be compressed, and a threaded spindle for engagement with the top of the valve rotatable in said frame for drawing said shoe towards said spindle to compress a valve spring.

2. A valve spring compressor comprising a frame having a plurality of spaced apart 75 annular openings therein, an arm angular in cross section adapted to be positioned in any one of said openings, a shoe on the lower end of said arm for engaging the spring to be compressed, and a threaded spindle for 80 engagement with the top of the valve rotatable in said frame for drawing said shoe towards said spindle to compress a valve spring.

3. A valve spring compressor comprising 85 a frame having a plurality of spaced apart openings with slots adjacent thereto, an arm threaded at its upper end adapted to be positioned in any one of said openings, a nut having a flange adapted to be positioned 90 in one of said slots for adjustably supporting said arm in said frame, a laterally-extending foot on the lower end of said arm, a shoe of suitable length removably secured to said foot for engaging the spring to be compressed, and a threaded spindle rotatable in said frame for engaging the upper end of 95 said valve to lift the frame and its shoe whereby the spring may be compressed.

4. A valve spring compressor comprising 100 a frame having a T-shaped slot therein with an opening through said frame leading from said slot and at substantially right angles thereto, an arm extending through said opening and threaded at its upper end, a nut having a flange in said slot and in threaded engagement with said arm to adjustably support said arm, a bifurcated shoe on the lower end of said arm for straddling a valve stem and engaging a spring, and means for 105 engaging the upper end of the valve and raising said shoe for compressing a valve spring.

5. In a valve spring compressor, a shoe having a bifurcated end to straddle a valve stem, and upstanding projections on said end located for engaging beneath substantially diametrically opposite points of the valve spring through which pressure to said spring is applied.

6. In a valve spring compressor, a shoe having a bifurcated end to straddle a valve stem having a recess in said end to fit the lower end of said spring and projections in said recesses located to engage substantially diametrically opposite points on the lower end of the valve spring through which the compressing pressure of the spring is applied.

7. In a valve spring compressor, a shoe having a bifurcated end to straddle a valve

stem and having a recess in said end to fit the lower end of said spring, and projections in said recesses located to engage substantially diametrically opposite points on the lower end of the valve spring through which the compressing pressure of the spring is applied, said projections being located in

substantially axial alignment with the valve stem and the point of application of lifting pressure whereby the lifting pressure is applied in alignment with the axis of the valve stem. 10

In testimony whereof I affix my signature.
SAMUEL ANGROVE.
